UNITED STATES PATENT OFFICE.

SEDWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

SIGNALING SYSTEM FOR SINGLE-TRACK ROADS.

Application filed December 10, 1920. Serial No. 429,702.

To all whom it may concern:

Be it known that I, SEDGWICK N. WIGHT, a citizen of the United States, residing at Rochester, in the county of Monroe and 5 State of New York, have invented certain new and useful Improvements in Signaling Systems for Single-Track Roads, of which the following is a specification.

This invention relates to block signal systems for single track railroads of the type 10 commonly known as an absolute-permissive-block system.

In one type of an A. P. B. system, such as described, for example, in my prior Patent No. 1,294,736, dated Feb. 18, 1919, if 15 two opposing trains happen to pass simultaneously the starting signals at the opposite ends of the stretch of single track between the passing sidings, a lock-up condition occurs which leaves all of the signals of 20 that stretch of track at stop, regardless of train movement. Such a condition will only occur when there is an unauthorized train movement, or other abnormal condition, but 25 since the result is to compel all trains to flag through that single track block until the lock-up condition is corrected, additional facility of train movement would be provided, if the system is so constructed and arranged 30 that this lock-up condition will be automatically removed when the train at fault backs out of the single track block.

One of the principal objects of the present invention is to provide a system of the 35 type described in which the signals may assume their regular working condition after a simultaneous movement of two opposing trains past the starting signals, as soon as one of these trains backs out of the single 40 track block.

Other specific objects and advantages of the invention will appear as the description of the invention progresses, and the novel features will be pointed out in the appended 45 claims.

For the purpose of explaining the need and utility of the present invention there is shown in the accompanying drawings part 50 of the complete A. P. B. system shown in detail and fully described in my prior patent above mentioned, with the present invention incorporated therewith; but it should be understood that the invention is not limited to this specific system and may be embodied in other specific forms in connection

with other similar A. P. B. systems by making the appropriate detail changes.

In the accompanying drawings,

Fig. 1 shows in a diagrammatic and simplified way one arrangement of signals for 60 an A. P. B. system;

Fig. 2 shows in a simplified manner a portion of single track adjacent to one siding, together with the signals, relays, and controlling circuits associated with this portion 65 of track, and constituting that part of the complete system shown in my prior patent with which the device and circuits embodying the present invention are associated;

Fig. 3 is a diagrammatic view similar to 70 Fig. 2, with some relays and circuits omitted, which shows one form of the invention; and

Figs. 4, 5 and 6 are diagrammatic views similar to Fig. 3, which illustrate modified forms of the invention.

Referring to Fig. 1, there is illustrated a stretch of single track (indicated by the single, heavy line) and a passing siding S and S^1 at each end of this stretch. The stretch is divided in the usual manner into 80 a number of track sections A, B, C etc. Signals 5, 6, 7 and 8 govern traffic from right to left, in the direction indicated by the arrow Y; and signals 9, 10, 11 and 12 govern traffic from left to right, in the direction indicated by the arrow X. The signals 8 and 9 at the ends of the stretch are 85 provided with square ended blades and marker lights so as to be distinguishable from the other intermediate signals, said 90 signals 8 and 9 being commonly known as the starting or absolute signals.

Referring now to Fig. 2, there is illustrated a portion of the system between the signals 9 and 10. The track rails 1 and 2 95 of the track are divided by insulated joints 3 into electrically isolated track sections A, B, C and D. Each of these track sections is provided with a track battery 4 and a track relay in the usual way, the track relays being designated 13-16. Associated with the signals 9, 6 and 10 are relays hereinafter termed line relays, which are designated 17, 18 and 19, respectively. Also associated with these signals, are stick relays 20, 21 100 and 22.

Since the various relays and circuits associated with the several signals are in general the same, a description of those associated with one signal 9 will suffice to give 110

a clear understanding of the present invention.

The signal 9 is controlled by a line relay 17, so that when this relay is energized, the 5 signal mechanism is applied with current and acts to hold said signal in its vertical or proceed position. The operating circuit for the signal 9 may be traced from B, front contact 23 of the line relay 17, wire 24, 10 through the signal mechanism, to N.

In the circuits illustrated, the batteries have not been shown, and the notations B, 15 N and K are used in accordance with established convention to show the path for current in the various circuits. It should be understood that a local battery is located at each signal, one terminal of this battery being connected to a common wire extending along the track. Some of the circuits are 20 local and are indicated as terminating at B and N. Other circuits extend from one signal location to another and are indicated by notations B and K.

The energizing circuit for the line relay 17 25 may be traced as follows: Commencing at the common wire K, relay 17, wire 25, front contact 26 of track relay 14, wire 27, front contact 28 of track relay 15, wire 29, back contact 30 of stick relay 22 of the opposing signal 6, wire 31, and thence either through front contact 32 of the line relay 18 of signal 30 10, or through the front contact 33 of the stick relay 21 of said signal 10, to B.

Thus, it will be observed that the line 35 relay 17 is deenergized, and the signal 9 put to stop in case:—(1) either of the track sections B or C is occupied; (2) the stick relay of the opposing signal 6 is picked up; and (3) if the line relay 18 of the next 40 signal 10 in advance is deenergized, and the corresponding stick relay 21 is not energized at that time. The line relay 18 of signal 10 is in turn controlled in a similar way by a line relay at signal 11 (see Fig. 1), and 45 the latter line relay in turn controlled by the track circuits F and G, with the result that a train entering the stretch of track on to the track section G causes successive dropping of the line relays of signals 11, 50 10 and 9 and puts these signals to stop. The stick relays associated with these signals are deenergized at that time.

The energizing or pick-up circuit for the stick relay 20 may be traced as follows: 55 Commencing at the negative battery N, relay 20, wires 34 and 35, back contact 36 of the track relay 14, wire 37, and circuit controller 38 operated by signal 9. The circuit controller 38 is illustrated in accordance 60 with established convention and is operated in accordance with the movement of the semaphore blade. It maintains its contacts closed for a portion of the movement of the semaphore, from its proceed position toward 65 its biased position.

A train, traveling from left to right, when it enters the track section B, closes this pick-up circuit for the stick relay 20, because back contact 36 of the track relay 14 is closed, and the circuit controller 38 of 70 the signal 9 is also closed, since the signal 9 is in the proceed position, otherwise the train would not enter this track section. A train traveling in the opposite direction, however, puts the signal 9 to stop before it 75 gets on the track section B, so that the pick-up circuit for the stick relay 20 is broken at the circuit controller 38. In this way the stick relay 20 is energized when a train passes the signal 9 in the direction in which 80 this signal governs traffic, but is not picked up by a train traveling in the opposite direction.

When the stick relay 20 has been energized, it is maintained energized by a stick 85 circuit, which may be traced as follows: Commencing at the negative battery N relay 20, wires 34 and 39, front contact 40 of said stick relay 20, wire 41, and back contact 23 of the line relay 17, to B. This stick 90 circuit is maintained so long as the line relay 17 is deenergized.

Assuming a train, traveling from left to right (in the direction indicated by the arrow X), passes the signal 9 and enters track 95 section B, the signal 9 is then put to stop, on account of the opening of the circuit for the line relay 17 at the front contact 26 of the track relay 14. In a similar way the line relay 19 is deenergized when track relay 14 drops, and puts the signals 6 to stop. The dropping of line relay 19 in turn drops the line relay of signal 7, putting that signal to stop, and the line relay of signal 7 in turn drops the line relay of signal 8, 100 putting this signal to stop, thereby blocking all opposing train movements. As the train in question passes from the track section B into the track section C, conditions remain unchanged. When the train passes 105 signal 10, it causes dropping of line relay 18, so as to put the signal 10 to stop, and also makes another break in the line circuit for line relay 17 at front contact 32. The stick relay 21, however, is picked up in the 110 same way as above explained in connection with stick relay 20, so that when the train leaves the track sections B and C, the line relay 17 may again pick up and cause the signal 9 to clear. It is noted at this point 115 that the control circuits and devices for governing the diagonal or caution position of the signals has not been shown in the circuit arrangements, in order to avoid unnecessary complication, this caution control being obtained in accordance with any of the well-known systems, such as shown in my prior patent above mentioned. When the train 120 enters track section D, it opens another break in the line circuit for signal 7. When 125 130

the train leaves track section C, line relay 19 may pick-up, and the signal 6 clear. As the train in question proceeds further past the signal 11, the same operation is repeated.

5 Referring to the line circuit of line relay 17 hereinbefore traced, it will be observed that this circuit is taken through the back contact 30 of the stick relay 22 associated with the next opposing signal 6. Thus, the 10 signal 9 cannot clear while the stick relay 22 is picked up. This same interlock between the line relay of each signal and the stick relay of the next opposing signal, is carried through the system. The purpose of this 15 interlocking arrangement is to check the operation of the stick relays. In the case of the signal 9, for example, the stick relay 22, which is picked up by a train traveling from right to left, is never picked up in the normal 20 operation of the system, when it is permissible for the signal 9 to clear. If the stick relay 22, however, should for any reason be improperly energized, it would allow the signals 7 and 8 to stay in the clear position 25 even though a train, moving in the direction of the arrow X, should enter the track section B, and drop line relay 19, since the stick relay 22 would keep the line relay of signal 7 energized, provided this checking 30 arrangement were not employed. With such a checking arrangement, however, the signal 9 could not clear if the stick relay 22 should be picked up.

This checking arrangement offers additional incidental protection. Suppose, for instance, that signal 6 should be mechanically stuck in its proceed position. A train moving from left to right, in the direction indicated by the arrow X, would energize 35 the stick relay 20 in the regular way; and as this same train entered track section C, the stick relay 22 would also be energized, since signal 6 will not have moved from its proceed position, as it should. With the stick 40 relay 20 energized, the line relay 19 can not be energized; and likewise, with the stick relay 22 picked up, the line relay 17 can not be picked up. As long as the line relay 17 is deenergized, the stick circuit for relay 20 is 45 maintained; and likewise, so long as line relay 19 is down, stick relay 22 is held up. Thus, a lock-up condition would result, and regardless of train movement, the opposing signals 6 and 9 could not clear, showing 50 that something was wrong.

This same lock-up condition, described in connection with signals 6 and 9, can also happen when the stick relays associated with the signals 9 and 8 at the ends of the stretch 55 are both picked up. In other words, if two trains should happen to enter the track sections B and G at approximately the same instant, the stick relays at each of the signals 8 and 9 would be picked up, thereby producing said lock-up condition, and train move-

ments in both directions would be blocked until this lock-up condition is broken by hand. This would compel the trains to flag through this stretch of track until the system is restored to normal.

The present invention is designed to permit automatic restoration of the system to normal, after the lock-up condition above explained occurs. It will be observed that this lock-up condition is due to the fact that 70 the stick relay of each signal is controlled by its line relay, which in turn is controlled by the opposing stick relay. If the stick circuit of the stick relay were not controlled by a line relay, or if the line relay were not controlled by the opposing stick relay, this locked up condition would not occur. Obviously, therefore, one remedy for the problem under consideration, is to omit the back contact, as 30, on the stick relay at one end, 75 or both ends of the stretch. This would break up, so to speak, the operating chain which causes the lock-up condition; but at the same time the protection afforded by checking the line circuit of the first opposing 80 intermediate signal, as 6, through the opposing stick relay, as 20, would be lost.

Another solution of the problem, which is shown in Fig. 3, is based upon the idea of maintaining the stick circuit for the stick 90 relay 20 closed at the proper time and as long as desired, without controlling it by the line relay, or something governed by the line relay. In the specific arrangement illustrated in Fig. 3, the stick circuit for relay 100 20, instead of being taken through the back contact of the corresponding line relay 17, is taken through the back contact 42 of an auxiliary or repeater relay Z, controlled by the track relays 14 and 15 of the two track 105 sections B and C. The circuit for the auxiliary relay Z may be traced as follows: commencing at the common wire K, relay Z, wire 43, front contact 44 of track relay 14, wire 45, front contact 46 of track relay 15, to 110 B. When two trains enter opposite ends of the stretch of single track at the same time, the two stick relays associated with signals 9 and 8 pick-up the same as before, but when one of these trains gets off of the track circuit 115 B and C, the stick relay 20 drops, because its stick circuit is broken. The dropping of this stick relay 20 allows signal 6 to clear and so on, automatically removing the lock-up condition and restoring the system 120 to normal. At the same time the line circuit of each signal is checked through the back contact of the opposing stick relay, so that this stick relay can not be improperly stuck up without detection. By providing a 125 relay Z at both ends of the stretch of single track, the lock-up condition can be broken if either train backs out.

Fig. 4 illustrates a modified arrangement of circuits to carry out the same idea as those 130

shown in Fig. 3. In Fig. 4, the stick circuit for the relay 20 includes back contacts 47 and 48 of the track relays 14 and 15, in multiple, so that so long as either of the 5 track sections B or C is occupied, said stick circuit is maintained. This arrangement operates in the same way as originally explained in connection with Fig. 3.

Fig. 5 illustrates still another way of 10 automatically restoring the system to normal after the lock-up condition has occurred. According to this modification, provision is made for knocking down the stick relay, as 15 20, associated with one or both of the starting signals, when a train that has entered the stretch of single track backs out. Referring to Fig. 5, the pick-up and stick circuits for the stick relay 20 are the same as 25 shown in Fig. 2, except that the negative battery N, is taken through a back contact 49 of an auxiliary relay W, so that when this relay W is picked up, the relay 20 is de-energized.

The energizing circuit for relay W may 30 be traced commencing at N, relay W, wire 50, back contact 51 of track relay 13, wire 52, front contact 53 of track relay 14, wire 54 and circuit controller 55 closed with the signal 9 in the horizontal or stop position.

35 This control of the auxiliary relay W is such that said relay is not energized when a train travels from left to right in the direction indicated by the arrow X, but is energized when a train, starting in this direction, reverses its direction of movement and backs up into track section A out of track section B. When a train traveling from left to right enters track section A, the circuit for relay W is closed at the back contact 51, 40 but is open at the circuit controller 55 (it being assumed that there is no train in the stretch.) As this train proceeds it opens said circuit for relay W at the front contact 53 before said circuit is closed at the circuit controller 55, and when the train has proceeded far enough to allow track relay 14 to 45 pick up and close its front contact 53, the rear end of said train has passed off of the track section A, with the result that said circuit for relay W is now broken at back contact 51. Thus, the relay W is not energized by a normal train movement from left to right, this train movement being the one 50 picked up. Consequently, relay W does not interfere with the regular operation of the system. Suppose, however, the train, after getting into track section B, backs up. Circuit controller 55 is closed, having been closed when the train entered track section 55 B. Back contact 51 is closed, because the train is now on track section A. Consequently, during the interval after the closing of the front contact 53 and opening of the circuit controller 55, the energized circuit 60 for relay W is established, and the stick

relay 20 is deenergized. If desired, this interval may be increased by making the circuit controller 55 so that it makes contact during a portion of the movement of the signal 9 upward from its stop position.

70 Referring to the operation of the modification shown in Fig. 5, if two trains should happen to enter opposite ends of the stretch at about the same time, the stick relays associated with the signals 9 and 8 would pick up, and the lock-up condition hereinbefore explained would result. These two trains could not proceed according to signal indications, and even if they attempted to flag through, one would have to back up until 75 behind its corresponding starting signal 8 or 9. This back-up movement would pick-up the corresponding auxiliary relay W and drop the corresponding stick relay, as above explained; and consequently the lock-up condition would be broken.

75 It will be evident that the stick relay, as 20, at the starting signals 8 or 9, may be de-energized or knocked down by a back-up movement of a train, by specific arrangements of circuits and devices other than the one shown in Fig. 5. For example, in one arrangement shown in Fig. 6, the stick relay 20, is knocked down by a back-up movement 80 as described, by shunting out said relay 95 through a suitable resistance 56 to avoid short circuiting the battery. The same back contact 51 of track relay 13, the front contact 53 of track relay 14, and circuit controller 55 of signal 3 are employed in this 100 modified arrangement shown in Fig. 6, as in the arrangement shown in Fig. 5, the circuit including the shunting resistance 56 being closed under the same conditions of train movement previously explained.

105 From the foregoing it will be observed that I have provided improved arrangements of circuits and devices, by means of which train movement is facilitated in case two trains should happen by accident to enter opposite ends of the stretch of single track at approximately the same instant, while at the same time retaining the safety feature of checking the deenergization of the several stick relays; and while I have 110 shown my invention incorporated with a specific type of an absolute-permissive block system the same principles may be applied to other types of systems. I desire to have it understood, therefore, that the specific arrangements of circuits and devices shown and described are merely illustrative of the invention, and do not exhaust the various physical embodiments of the idea of means constituting the invention.

115 What I claim as new and desire to secure by Letters Patent of the United States, is:—

120 1. In a signal system for single track railroads having two sets of signals at intervals along a stretch of single track between two 125

130

passing sidings and governing traffic in opposite directions, stick relays associated with said signals and automatically energized by a train moving in the direction of traffic 5 governed thereby, a line circuit for each signal including a back contact of the stick relay associated with the next opposing signal; a stick circuit for each relay controlled by the line circuit of the corresponding signal, and means associated with each of the starting signals at the ends of said stretch for causing deenergization of the corresponding stick relay when a train moves by that signal opposite to the direction of traffic 10 governed thereby.

2. In a signaling system of the type specified in claim 1, the combination with the starting signal at the end of the stretch and the stick relay associated therewith, of 20 means for interrupting the stick circuit of said relay when a train passing a signal in the direction of traffic governed thereby backs up into the track section in the rear thereof.

25 3. In a signaling system of the type specified in claim 1, the combination with each of the starting signals at the ends of the stretch of single track and the stick relays associated therewith, of means dependent upon 30 the direction of movement of trains past said signals for governing the stick circuit of the corresponding stick relay.

4. In a signal system of the type specified in claim 1, the combination with each of the 35 starting signals at the ends of the stretch of single track and the stick relay associated therewith, of means including front and back contacts on the track relays of the track sections adjacent to each signal for governing the stick circuit of the corresponding stick relay.

5. In a signal system of the type specified in claim 1, the combination with the starting signal at one end of the stretch of single 45 track and the stick relay associated therewith, of a slow acting circuit controller governed by the line circuit of said signal and opened or closed when said line circuit is energized and deenergized respectively, and 50 means for controlling the energization of said stick relay, said means comprising a circuit including said circuit controller and front and back contacts respectively of the track relays of the track sections next in advance and in the rear of said signal.

6. In a signal system for single track railroads having two sets of signals governing traffic in opposite directions over a stretch of single track between two passing sidings, 60 a directionally controlled device associated with said signals and responsive to the direction of movement of trains, said device of each signal acting when active to hold the next opposing signal at stop, and means 65 associated with the starting signals at the

ends of said stretch for automatically restoring the corresponding device to the normal condition when a train having entered the stretch from that end backs up out of the track sections in advance of the corresponding starting signal. 70

7. In a signal system for single track railroads having two sets of signals governing traffic in opposite directions over a stretch of single track between two passing sidings, 75 a line circuit for each signal controlled by the track relay of the track sections protected thereby, the line circuit of each signal being controlled by the line circuit of the signal next in advance which governs traffic 80 in the same direction, a directionally controlled device associated with each signal and changed to an active condition by a train moving in the direction of traffic governed by that signal, said device of each signal acting when active to hold the next opposing signal at stop, and means associated with the starting signals at the end of the stretch for maintaining the corresponding device active 85 when once rendered active so long as a train 90 causing such change occupies the track section protected by that signal, said means automatically restoring said device to the normal condition when such train reverses 95 its direction of movement and backs out of the track sections protected by the corresponding starting signal.

8. In a signal system for single track railroads having a stretch of track between two passing sidings, the combination with a 100 signal at one end of the stretch governing movement of trains into the stretch, of a device rendered active by the movement of trains in the direction of traffic governed by said signal and maintained active while such train occupies a certain portion of the stretch, and automatic means for independently restoring said device to the normal condition when such train reverses its direction 105 of movement and backs out of said certain 110 portion of the stretch.

9. In a signal system for single track railroads having a stretch of single track between two passing sidings, the combination with signals at opposite ends of the stretch 115 and governing train movement into the stretch, of a normally deenergized stick relay associated with each signal and automatically energized by a train moving in the directions of traffic governed thereby, and 120 means for causing deenergization of each stick relay when a train having passed the corresponding signal in the direction of traffic governed thereby backs up in the rear of that signal. 125

10. In an absolute-permissive-block signal system for single track railroads of the type described, the combination with the starting signal at the end of the stretch of single track, a normally deenergized stick relay as- 130

sociated with said signal, pick-up and stick circuits for said relay, and means governing both the pick-up and stick circuits of said relay, comprising front and back contacts of 5 track relays of track sections adjacent to and on opposite sides of the signal.

11. In an absolute-permissive-block signal system for single track railroads of the type described, the combination with the starting 10 signal at the entrance to the stretch of single track, a stick relay, pick-up and stick circuits for said relay, and means governing both the pick-up and stick circuits of said relay, comprising a normally opened circuit 15 controller closed when the track circuits next in advance of the signal are occupied.

12. In a signal system for single track railroads having a stretch of single track between two passing sidings, a starting

signal at one end of the stretch, a normally closed circuit controller operated by the signal and opened during movement thereof to its biased stop position, a stick relay, a pick-up circuit for the relay including said circuit controller and a back 25 contact of the track relay next in advance of said signal, a line circuit governed by a plurality of track circuits in advance of the signal, a stick circuit for said relay closed at one point when said line circuit 30 is deenergized, and means comprising front and back contacts of track relays adjacent to and on opposite sides of said signal for governing the continuity of both the pick-up and stick circuits of said relay. 35

In testimony whereof I affix my signature.

SEDGWICK N. WIGHT.
